UNITED STATES PATENT OFFICE.

WALTER L. BARTHELEMY, OF DAYTON, OHIO.

INTERNAL-COMBUSTION ENGINE.

1,284,043.

Specification of Letters Patent.

Patented Nov. 5, 1918.

Application filed April 22, 1918. Serial No. 229,978.

To all whom it may concern:

Be it known that I, WALTER L. BARTHELEMY, a citizen of the United States, residing at Dayton, in the county of Montgomery and State of Ohio, have invented certain new and useful Improvements in Internal-Combustion Engines, of which the following is a specification, reference being had therein to the accompanying drawing.

10 This invention relates to internal combustion engines and its principal object is to provide an improved engine of the rotary type containing a plurality of separate cylinders, the pistons of which reciprocate, thus avoiding entirely the turbine principle. The gas is exploded in the several cylinders and acts on reciprocating pistons, these pistons being engaged and disengaged with stationary portions of the engine 20 frame.

An additional object is to provide an improved engine of the type referred to having cylinders mounted on a rotating frame; these cylinders having pistons acting against stationary bars, both to compress the gas in the cylinders and to cause rotation of the cylinders. The cylinders are carried by the rim of the rotating frame or wheel and thus have very large leverage on the cross rods 30 against which they operate, whereby a large torque is produced.

A further object is to provide such an engine with a large number of small cylinders, the number of which can be increased as desired so as to produce a very even torque on any driven device. The amount of power can be varied by the use of additional cylinders and the construction provides readily for the attachment of such additional cylinders.

40 A further object is to provide such an engine made in sections, each having a plurality of cylinders so that the engine may be furnished in different sizes by the mere addition of other cylinders and their supporting parts.

An additional object is to provide an engine of the type described working on the two cycle principle and in which the gas is 50 forced into the cylinders under pressure and then compressed by the movement of the pistons in the cylinders.

In the drawings, Figure 1 is a side elevation of the complete engine showing the 55 cylinders mounted on the rim of the rotating frame and indicating the stationary

frame supporting the rotating parts; Fig. 2 is a vertical section taken centrally of Fig. 1 on the line 2-2 and in the direction of the arrow on Fig. 1; and Fig. 3 is a detail 60 enlarged section on the line 3-3 of Fig. 1, the position of the parts being such as to show the gas entering the cylinders under pressure.

The construction includes a rotating 65 frame on which cylinders are mounted in sets or groups, each group comprising a number of cylinders. These cylinders are pivoted at the rim of the frame and are adapted to oscillate on the frame, this oscillation being caused by the engagement of the pistons in the cylinders with certain cross rods of the stationary frame which supports the rotating parts. In operation the gas or fuel enters the cylinders under 70 pressure and is then compressed in the cylinders by the movement of the rotating frame, which movement causes the pistons to engage the cross rods referred to and be held momentarily thereby. When the gas has 75 been compressed it is exploded and drives the pistons in the cylinders, thereby causing movement of the rotating frame through the engagement of these pistons with the cross rods before referred to. The gas is carried 80 into the cylinders through the axle and the spokes of the rotating frame to the rim which is hollow for the purpose of permitting the passage of the gas. Valves in this 85 rim are controlled by the cylinders in their 90 oscillating movement and thus entrance of the gas to the cylinders is permitted only at the desired point.

As shown, the engine is built in sections which may be duplicated as desired, whereby to increase the power of the engine 95 readily.

Referring to Fig. 2 the stationary frame 1 is mounted on a desired support and it includes members 2 and horizontal cross rods 100 3. The central portions of the members 2 are arranged to form journals 3^a in which the shaft 4 of the rotating frame is carried. As shown, the shaft 4 is hollowed at 5 so as to permit passage of the gas and the spokes 105 6 are also hollow, thus permitting the gas to pass to the rims 7. These rims have circular passages 8 so that the gas may freely circulate entirely around the rim and thereby may pass out of any of the valve ports 110 carried in the rim.

It will be seen that the construction pro-

vides a plurality of sections of the machine each having a series of spokes 6 and a rim 7, these sections all being carried on the common central shaft 4 and each section including a plurality of driving cylinders.

Fig. 1 shows the position of the several cylinders around the rim 7 and in this figure there are shown seven cylinders. Of course, this number is not essential and more or less may be employed. These cylinders 10 are pivotally mounted on the rim 7, pivots 11 constituting cylinder journals being employed for that purpose. Thus, the cylinders may oscillate relative to the rim as they are being rotated by the movement of the rotating frame. The cylinders are provided with pistons 12 having piston rods 13 which at their outer ends are provided with bifurcated portions 14 adapted to engage the cross rods 3 of the stationary frame. The engine as stated operates on the two cycle principle and each cylinder is therefore provided with an exhaust port 15 and with a gas inlet valve 16. This valve is pressed by a spring 17 toward closing position, as indicated in Fig. 2. As no crank shafts or connecting rods are employed the extent of travel of the pistons 12 must be controlled so as to prevent these pistons from striking the outer ends of the cylinders. To this end springs 18 surround the piston rods 13 and it will be evident that in the outward movement of the pistons they will engage these springs and compress them, thereby stopping the movement of the pistons in the cylinders and preventing damage. Clearly, when the pistons 12 cover the exit ports 15 the air thus confined will be compressed by the further movement of the pistons and this aids in stopping the pistons gradually and before they reach the outer ends of the cylinders. In order to provide a second journal for the cylinders yokes 19 are employed carried by the rim 7, these passing entirely around the cylinders and providing bearings 20 for the shaft 21 around which the cylinders oscillate.

As stated, the cross rods 3 control the oscillation of the cylinders 10 in one of their movements and additional devices are provided for causing the reverse oscillating movement. Fig. 1 shows the several cylinders in different positions relative to the cycle of firing. The cylinder at the top of Fig. 1 marked 10^a is in firing position, its piston rod 13 being directly radial from the shaft 4 to the particular cross rod 3. The cylinder next to the right in Fig. 1 marked 10^b is on the compression stroke. That is, the gas has been admitted to the cylinder through the shaft 4 and the spoke 6 and the piston is being forced inwardly in the cylinder by the rotation of the frame and through the engagement of the piston rod 65 with the corresponding cross rod 3. This

compression will continue until the particular piston rod 13 for the cylinder 10^b is directly radial from the center of shaft 4. The cylinder near the bottom of Fig. 1 marked 10^c has nearly completed its compression stroke and will shortly be fired. The cylinder marked 10^d has been fired and the cylinder itself is moving away from the corresponding cross rod 3 and its piston 12 is therefore passing outwardly through the cylinder. The cylinder 10^e is in the charging position, that is, its piston rod 13 is fully extended and the valve 16 of the cylinder is in operative relation with the valve in the rim so as to permit the gas to pass. The cylinder 10^f has substantially completed its operative stroke, the piston rod being nearly extended and the piston 12 having about reached a position where the exit port 15 is uncovered. Obviously, the rotation of the frame will shortly move this cylinder 10^f enough to carry the bifurcated portion 14 of its piston rod away from the cross rod 3.

It will be seen that the cylinder 10^f must shortly be disengaged from the cross rod 3 and moved to such a position that its piston rod may engage the succeeding cross rod 3 which in the case of the cylinder mentioned is at the top of Fig. 1. That is, the cylinder 10^f must shortly assume a position relative to the rim similar to that shown for the cylinder 10^e. To accomplish this requires a reverse oscillation of the cylinder as compared with its oscillation given by its engagement of the piston rod with the cross rod 3. To cause this reverse oscillation the stationary frame portions 2 are provided with a series of short circular racks 22 and the supporting shafts 21 of the cylinders are provided with pinions 23 adapted to be moved over the stationary racks 22. The racks appear in Figs. 1 and 3 and it will be seen that they are positioned between the cross rods 3 and at points such that the pinions 23 will engage the first tooth of the particular rack 22 just as the piston rod 13 leaves the corresponding cross rod 3. This position is indicated in connection with the cylinder 10^f on Fig. 1 and it will be seen there that the pinion 23 will very shortly engage the stationary rack 22. Obviously, the further movement of the rotating frame will oscillate the cylinder 10^f in the desired direction so as to bring it in some such position relative to the rim as the cylinder 10^e occupies in Fig. 1. This is done as the cylinder moves past the particular rack 22 and is completed by the time the gear 23 leaves the rack 22 so that at this time the piston rod 13 is in the proper position to have its bifurcated portion 14 shortly engage the succeeding cross rod 3 and be stopped thereby.

It will be seen that the principle of the

invention is that the piston rods engage stationary projections and are therefore stopped so as to cause compression of the gas in the cylinders by the rotation of the wheel or rotating frame. When the piston has completed its compression stroke and the cylinder is in the position shown at 10^a in Fig. 1 the explosion occurs and the piston is driven outwardly through the cylinder. This causes the rotating movement of the rim by engagement of the piston rod with the stationary cross rod 3. As soon as the particular cylinder has expended the energy of its fuel it is necessary to repeat the operation in connection with the succeeding cross rod 3 and this is accomplished by the oscillation of the cylinder through engagement of the pinion 23 with the stationary rack 22.

20 In Fig. 2 the cylinders shown at the bottom of the figure are in firing position, their pistons 12 being at the upper ends of the cylinders and the piston rods engaging the particular cross rod 3. Here the valve 16 is closed so as to prevent the fuel from passing out of the cylinder and the explosion is caused as usual by an electric spark furnished by the spark plug 26. The stationary frame portions 2 are provided with 30 circular contact bearing members 27 and 28 and the spark plug head is arranged to touch the member 27, the circuit being completed through the cylinder 10 and a projection 29 formed thereon, this projection engaging 35 the other contact member 28. The means for producing the electric current at the proper instant and distributing it to the various cylinders is not shown as any of the well known methods may be employed. 40 To advance or retard the spark the contacts 27 and 28 are mounted on circular members 30, these members being carried on the stationary frame 2 and being adapted to be slightly rotated by hand operated devices 31. The turning of these devices 31 will obviously move the contact members 27 and 28 slightly and thus change as desired the exact timing of the explosions.

Fig. 3 shows the parts in the position in which gas is admitted to the cylinders. It will be remembered that the gas is forced through the hollow rim 7 under pressure and there are provided valves 32, one for each cylinder, these valves seating against valve seats 33 formed on the rim 7 and being normally pressed outward by springs 34. A rod 35 carried on a cross portion 36 of the rim 7 serves to guide the valves 32. The spring 34 together with the gas pressure is sufficient to overcome the spring 17 of the valve 16 and thus when the two valves are in operative relation, as shown in this figure, they will both open and gas pass into the cylinders. As shown, the valve 65 16 is provided with an end plate 37 di-

rectly abutting the end of the valve 32. When the cylinder has been charged with gas its entrance to the cylinder must be shut off and this is caused by the oscillation of the cylinder before referred to. In 70 the position of cylinder 10^a in Fig. 1 the charging is taking place and a slight movement of the rotating frame will engage the piston rod of that cylinder with the cross rod 3, whereupon oscillation of the cylinder 75 on the rotating frame will begin. The first movement thereof will carry the valve 16 away from the valve 32 and then the return of gas past the valve 16 is prevented by the spring 17 which causes the valve to seat. 80 However, the springs 34 for the valves 32 constantly tend to press these valves outwardly or to their open position and this, of course, would permit escape and waste of the fuel. To prevent such waste each 85 of the cylinders is provided with a circular plate 41 adapted to move over the outer edge of valves 32 and hold them tightly seated. These circular portions extend to positions such that the very first movement of oscillation of the cylinders away from the charging position carries the plate 41 over the valve 32 before any gas has a chance to escape. These plates 41 hold the valves 32 tightly shut during the entire double oscillation of the cylinders and until they again 90 reach the charging position of cylinder 10^a.

It will be seen that the construction provides for an explosion in each of the cylinders as it passes each of the cross rods 3 100 in succession. In the form shown there are seven cylinders of each group and there are shown five of the cross rods 3. Thus each complete rotation of the frame will cause five explosions in each of the seven 105 cylinders, whereby a very even torque is produced and the engine is obviously capable of producing a large amount of power.

The number of cylinders is not an even multiple of the number of cross rods 3. 110 Obviously, if the number of cylinders and cross rods were equal the cylinders would all fire together and thereby much less even torque would be produced. In the form shown in Fig. 1 the order of firing of the 115 cylinders is as follows: 10^a, 10^b, 10^c, 10^d, 10^e, 10^f and 10^a. It will be observed that the cylinders which fire in succession are at substantially opposite portions of the rotating frame and that each movement of 120 10^a degrees of rotation of the frame causes the explosion of one cylinder. The particular number of the cylinders and the cross rods shown is not essential as it evidently may be varied with corresponding 125 variations in the number of explosions for each rotation of the frame and consequent varying of the torque produced.

Fig. 2 shows two sections of such an engine, each section comprising two sets of 130

cylinders. The cylinders are arranged in pairs on each of the wheel rims 7 so that with the form shown each section of the engine includes fourteen cylinders. The 5 number of sections may readily be increased as before indicated by extending the cross rods 3 and adding additional circular members 2 of the stationary frame, the central shaft 4 being common to all of the sections of the engine.

While the use of the racks 22 to cause the oscillations of the cylinders 10 so as to engage their piston rods with the cross rods 3 in advance thereof is the preferred form, 15 nevertheless others means to accomplish this function may be employed. As an example a strong spring may be attached to each of the cylinders constantly tending to move it to the position of cylinder 10^a in Fig. 1, 20 whereby the cylinders will be oscillated as soon as their piston rods are carried away from the cross rods 3. Also such springs may be employed to aid the racks 22 if desired.

25 As a matter of improvement the various spokes 6 are shown as provided with fan blades 41 to cause a rapid circulation of air through the machine and thus aid in cooling the cylinders. Of course, the rapid movement of the cylinders themselves tends to 30 keep them cool, but the fan blades may be used if desired.

It is believed that the operation of the mechanism will be clear from the foregoing 35 description, but it may be briefly recapitulated by tracing the progress of one of the cylinders from one firing position to the next. In Fig. 1 the cylinder 10^a at the top of the figure is in firing position and at this 40 point the circuit is made through the contact members 27-28 to the spark plug 26, the circuit returning through the cylinder itself and its projection 29. As soon as the piston rod 13 leaves the position in which it is exactly 45 radial from the shaft 4 it presses against the stationary rod 3, thereby forcing the cylinder ahead or to the right in Fig. 1. The cylinder gradually moves to the relative position shown in connection with the 50 cylinder 10^f as its piston 12 moves outwardly and this movement continues until the piston covers the exit port 15 when the air in the lower portion of the cylinder begins to compress and is stopped by this compressed 55 air and by engagement of the piston with the spring 18. The further movement of the frame carries the piston rod away from the cross rod 3, this position being one which the cylinder 10^f will shortly assume 60 in the position of Fig. 1. Here the pinion 23 engages the stationary rack 22 and the cylinder is rapidly oscillated from the position of cylinder 10^f through the position of cylinder 10 finally reaching the position of 65 cylinder 10^e in which the piston rod en-

gages the cross rod 3 in advance. In this position the cylinder valve 16 and the rim valve 32 are in engagement and in operative relation with each other. Here the gas pressure through passage 8 in rim 7, together 70 with the spring 34, overcomes the spring 17 and opens these two valves, this position being shown in Fig. 3. The gas may then rush into the cylinder filling it, and as the frame moves the cylinder from the position 75 of cylinder 10^e to that of 10^b the cylinder valve 16 is moved away from the rim valve 32, whereupon both valves close, the valve 16 being closed by its spring 17 and the valve 32 being closed by the plate 41. Further movement of the cylinder moves it from the position of cylinder 10^b to that of cylinder 10^a, thereby compressing the fuel in the cylinder, and when the piston rod 13 is again radial from the shaft 4 the succeeding 85 explosion ensues. This operation is rapidly repeated as the frame rotates, each cylinder exploding as it passes each of the successive 90 cross rods 3.

While I have shown and described certain 90 features as constituting my invention, it will be understood that parts have been shown for purposes of illustration only, and that I do not desire to be limited to such details, as obvious modifications will occur to 95 a person skilled in the art.

Having thus fully described my invention, what I claim as new and desire to secure by Letters Patent, is:—

1. In an engine, the combination, with a 100 rotatable frame, of a plurality of cylinders mounted to oscillate on said frame, pistons and piston rods reciprocating in said cylinders, a stationary frame against portions of which said piston rods engage, and means 105 for oscillating said cylinders on said rotatable frame.

2. In an engine, the combination, with a 110 rotatable frame, of a plurality of cylinders mounted to oscillate on said frame, pistons and piston rods reciprocating in said cylinders, a stationary frame against portions of which said piston rods engage, valves on 115 said rotatable frame for admitting fuel to the cylinders, means for oscillating said cylinders on said rotatable frame, and devices carried by said cylinders for controlling said valves.

3. In an engine, the combination, with a 120 rotatable frame, of a plurality of cylinders mounted to oscillate on said frame, pistons and piston rods reciprocating in said cylinders, a stationary frame in which said rotatable frame is journaled and including rods against which said piston rods engage, 125 devices carried by said stationary frame constructed to oscillate said cylinders whereby to engage their piston rods with said stationary frame rods in succession, valves carried by said cylinders, and additional valves 130

carried by said rotating frame, the oscillation of said cylinders serving to bring said cylinder valves and said frame valves into operative relation with each other.

5 4. In an engine, the combination, with a rotatable frame, of a plurality of cylinders mounted to oscillate on said frame, pistons and piston rods reciprocating in said cylinders, a stationary frame including a plurality of rods against which said piston rods engage in succession and by which said cylinders are oscillated on said rotatable frame, valves for admitting fuel to said cylinders, and devices operated by oscillation of said

10 cylinders for opening and closing said valves.

15 5. In an engine, the combination, with a rotatable frame, of cylinders mounted to oscillate on said frame, pistons and piston rods reciprocating in said cylinders, a stationary frame in which said rotatable frame is journaled and having portions against which said piston rods engage in succession, devices, controlled by the oscillation of said cylinders, for admitting fuel thereto, and

20 means, carried by said stationary frame, for causing explosion of the fuel admitted to said cylinders.

25 6. In an engine, the combination, with a rotatable frame having hollow spokes and a hollow rim through which fuel may travel, of a stationary frame including cross rods, and in which said rotatable frame is journaled, cylinders mounted in trunnions on said rotatable frame, pistons and piston rods reciprocating in said cylinders, said piston rods being adapted to engage said cross rods of said stationary frame and to be disengaged therefrom by movement of said rotatable frame, valves in said cylinders and in

30 said hollow rim, the cylinder valves being positioned to be brought into operative relation with the rim valves by oscillation of said cylinders, and means for closing said rim valves.

35 7. In an engine, the combination, with a rotatable frame having hollow spokes and a hollow rim, through which fuel may be forced under pressure, and valves in said rim controlling the passage of fuel, of a stationary frame including cross rods and in which said rotatable frame is journaled, cylinders mounted to oscillate in said rotatable frame, pistons and piston rods reciprocating in said cylinders, the piston rods being engaged and

40 disengaged from said frame cross rods by movement of said rotatable frame, valves carried by said cylinders and brought into operative relation with said rim valves by oscillation of said cylinders, means carried by said cylinders for closing said rim valves, and means, adjustably carried by said stationary frame, for permitting electricity to enter said cylinders to cause explosion of the fuel in said cylinders.

45 8. In an engine, the combination, with a

rotatable frame having hollow spokes and a hollow rim through which fuel may be forced under pressure, and valves in said rim controlling the passage of fuel therefrom, of a stationary frame in which said rotatable frame is journaled, cylinders mounted to oscillate on said rotatable frame, pistons and piston rods reciprocating in said cylinders, said piston rods operating against elements of said stationary frame, devices for oscillating said cylinders to bring the piston rods in engagement with said frame elements, valves in said cylinders movable into operative relation with said rim valves, and means carried by said cylinders for closing said rim valves.

50 9. In an engine, the combination, with a stationary frame including cross rods, of a rotatable frame journaled in said stationary frame, a plurality of cylinders mounted to oscillate on said rotatable frame, the number of cylinders not being an even multiple of the number of cross rods, pistons and piston rods in said cylinders, said piston rods being constructed to engage said cross rods in succession, and means for conveying fuel to and exploding it in each cylinder each time the corresponding piston rod engages any of the cross rods.

55 10. In an engine, the combination, with a stationary frame including cross rods, of a rotating frame journaled in said stationary frame, a plurality of cylinders mounted to oscillate on said rotating frame, pistons and piston rods in said cylinders, said piston rods engaging said cross rods in succession and driving said rotating frame by such engagement, means for oscillating said cylinders on said rotating frame, whereby to engage said piston rods with said cross rods, and means controlled by oscillation of said cylinders for admitting fuel thereto.

60 11. In an engine, the combination, with a rotating frame having a hollow rim forming a fuel passage, of cylinders mounted to oscillate on said frame, pistons and piston rods reciprocating in said cylinders, means against which said piston rods engage to drive said rotating frame, valves in said rim, said valves normally tending to open to permit passage of fuel, valves in said cylinders, the oscillation of said cylinders bringing said rim valves and said cylinder valves into operative relation to permit passage of fuel through both valves and into the cylinders, and plates carried by said cylinders for holding said rim valves closed except when the cylinder valves are moved into said operative relation with said rim valves.

65 12. In an engine, the combination, with a stationary frame, of a rotatable frame journaled therein, cylinders mounted to oscillate on said rotatable frame, pistons and piston rods in said cylinders, the piston rods being movable into engagement with elements of

said stationary frame, whereby to drive said rotating frame, racks mounted on said stationary frame and positioned between said frame elements, and pinions mounted on 5 said cylinders positioned to be engaged with said racks by the movement of said rotating frame.

13. In an engine, the combination, with a stationary frame and a rotatable frame journaled thereon, said rotatable frame comprising 10 a plurality of wheels each including a wheel rim, together with a central hollow shaft on which said wheels are carried, a plurality of cylinders mounted to oscillate 15 on each wheel, pistons and piston rods in said cylinders, said piston rods being positioned to engage elements of said stationary frame, and means, carried by said cylinders

and controlled by the oscillation thereof, for permitting fuel to pass from said central 20 hollow shaft into all of said cylinders.

14. In an engine, the combination, with a rotating frame, and a cylinder mounted to oscillate on said frame, said cylinder having a piston and a piston rod reciprocating 25 therein, of a series of stationary elements evenly spaced around said rotating frame and into engagement with each of which said piston rod is successively brought, each element serving, first, to move said piston in 30 said cylinder to compress fuel therein, and, second, to resist the reverse movement of said piston rod caused by explosion of the fuel in said cylinder.

In testimony whereof, I affix my signature. 35
